UNITED STATES PATENT OFFICE.

THOMAS F. McCAFFERY, JR., OF COLORADO SPRINGS, COLORADO.

DRAWING INSTRUMENT.

Application filed October 7, 1924. Serial No. 742,202.

The device forming the subject matter of this application is a drafting tool combining, in a single instrument, a plurality of scales, a triangle, a protractor, and an eraser guard, and the invention aims to provide novel means for protecting and sustaining the protractor.

It is within the province of the disclosure to improve generally and to enhance the utility of devices of that type to which the invention appertains.

Although a preferred form of the invention has been shown, it will be understood that a mechanic, working within the scope of what is claimed, may make changes without departing from the spirit of the invention.

In the drawings:—

Figure 1 is a plan; and Figure 2 is a section on the line 2—2 of Figure 1.

The device forming the subject matter of this application may be made out of any desired material, includes a frame 1 of approximately triangular outline, the frame having an opening 2. A semi-circular protractor 3 is located in the opening 2 and is joined at its ends to one side member 4 of the frame 1, whereby said side member will form a base for the protractor. The other side members 5 and 6 of the frame 1 constitute guards for the protractor 3. An arm 7 extends from the intermediate portion of the protractor 3 to the place of juncture between said other side members 5 and 6 of the frame, and serves to hold the protractor 3 and the frame 1 against bending out of a common plane.

The side member 4 of the frame 1 has a projection 8, provided with an opening 9 which forms the center point of the protractor 3, the protractor being graduated in any suitable way. In the present instance, but not of necessity, the protractor is graduated, as shown at 10, in opposite directions, from 0 to 180°. The arm 7 has a slot 11, the axis of which coincides with the 90° mark of the protractor 3, the slot being beveled at its edges so that an eraser may be operated conveniently in the slot. Scales 12 of any desired sort are located along the outer edges of the members 4, 5 and 6 of the triangle or frame. The mem-

bers 4, 5 and 6 of the triangle or frame are equipped with elongated openings 14, and there are scales 15 on the triangle, along both the inner and outer edges of the openings 14. The members 6 and 5 of the triangle or frame are supplied with scales 16.

The general construction of the instrument is such that it combines the advantages of a triangle, a plurality of rulers or scales, an eraser guard, and a protractor. If a straight edge is made to coincide with the vertex of the angle formed by the outer edges of the parts 5 and 6 of the triangle, and with the 90° mark of the protractor 3, a pencil line may be drawn through the slot 11. This operation makes it unnecessary for the draftsman to use the center point 9 in drawing the aforesaid line. Moreover, the line can be drawn directly on the paper, within the contour of the triangle, and it is unnecessary to prick the point into the paper, at a point external to the triangle, remove the triangle, draw the line through the prick point on the paper, and then reset the triangle with the center point 9 in proper position.

Having thus described the invention, what is claimed is:—

In a device of the class described, a frame of triangular outline, and having an opening the edges of which, throughout a major portion of their length, are parallel to the outer edges of the frame, a semi-circular protractor in the opening and joined at its ends to one side member of the frame whereby said side member will form a base for the protractor, the other side members of the frame constituting guards for the protractor, and an arm extended from the intermediate portion of the protractor to the place of juncture between said other side members of the frame and serving to hold the protractor and the frame against bending out of a common plane, the arm having an elongated opening the prolonged axis of which passes through the external angle defined by the outer edges of said other side members, and through the 90° mark of the protractor.

In testimony that I claim the foregoing as my own, I have hereto affixed my signature.

THOMAS F. McCAFFERY, JR.
